No. 892,100.

PATENTED JUNE 30, 1908.

P. F. VOGEL.

STOCKING FINISHING AND STRIPPING MACHINE.

APPLICATION FILED MAY 28, 1902.

UNITED STATES PATENT OFFICE.

PAUL F. VOGEL, OF ST. LOUIS, MISSOURI, ASSIGNOR, BY MESNE ASSIGNMENTS, TO THE BUR-
SON KNITTING COMPANY, OF ROCKFORD, ILLINOIS, A CORPORATION OF ILLINOIS.

STOCKING FINISHING AND STRIPPING MACHINE.

No. 892,100.

Specification of Letters Patent.

Patented June 30, 1908.

Application filed May 28, 1902. Serial No. 109,383.

To all whom it may concern:

Be it known that I, PAUL F. VOGEL, citizen of the United States, residing in the city of St. Louis and State of Missouri, have invented certain new and useful Improvements in Stocking Finishing and Stripping Machines, of which the following is a specification, reference being had therein to the accompanying drawings.

10 My invention relates to machines for finishing stockings and consists in a mechanism to be used in connection with a singeing machine for the purpose of cleaning the singed particles from the goods of stripping the stockings from the boards upon which they are stretched and of conveying the boards back to the front of the singeing machines, all of which will be hereinafter fully described.

20 The details of my device will be more fully understood by reference to the accompanying drawings, in which:

Figure 1 represents a plan view of the machine embodying my invention with the dust 25 guard or upper casing removed. Fig. 2 illustrates a vertical section of the same taken on the line 2—2 of Fig. 1, and Fig. 3 shows a diagrammatic view of my device as applied to a singeing machine.

30 Referring to the letters indicating the several parts, A, represents the frame of the machine provided with bearings B and B¹, for the reception of the first set of feed rolls C and C¹. The roll C¹ has a projecting shaft 35 C² which carries fast and loose driving pulleys C³ and C⁴. At the rear of the machine are rolls D and D¹, constituting the second set of feed rolls, which are mounted in bearings E and E¹ and which are driven from the 40 shaft C² by means of spur wheels F, F¹ and F². Both sets of rolls are caused to turn in unison by means of intermeshing pinions G, G¹ and H, H¹, the first set of pinions being arranged respectively upon the shafts of the 45 rolls C and C¹ and the second pair being in a similar manner operatively connected to the rolls D and D¹. Between the first and second pairs of feed rolls are placed blast-pipes I and I¹, which have a multiplicity of small 50 openings or jets i and i¹ arranged adjacent to the path of travel of the material which is being fed from one set of rolls to the other.

The stockings J, which are to be treated for the purpose of removing adhering particles of dust and dirt incident to the singeing

process, are mounted on boards K, which are cut in the shape of the stockings as shown in Fig. 1.

At the rear of the second set of feed rolls is a table L, which may be of sufficient incline to cause the boards K after passing the second set of rolls to slide downward and pass between the rolls D¹ and D², but I prefer to use in this connection as a more positive feed a conveyer M, which consists of a belt passing over the table and around rollers D³ and D⁴. It is obvious with this arrangement that the boards after passing between the rolls D and D¹ will travel aided by the conveyer M, between rolls D¹ and D², and it will also be understood that in place of the train of rolls as indicated that is the rolls D, D¹ and D² a train of four rolls may be employed in order to lower the path of return and provide as will presently be seen more space for the stripping brushes. The stripping brushes as indicated at N and N¹ are arranged directly forward of the rolls D¹ and D² and are mounted respectively upon shafts n and n¹ which have bearings in the frame A. The stripping brushes are geared together by spur wheels O and O¹ and motion is imparted to them by means of a belt pulley P¹.

The boards after passing between the brushes are released from the action of the rolls D¹ and D² and forwarded by the rolls D⁴ and D⁵ which pass the boards over the rod R, to the conveyer S. The roll D⁴ is driven from the shaft of the roll D¹, by means of a belt D⁶ engaging pulleys D⁸ and D¹⁰ the former being mounted on the shaft of the roll D⁴ and the latter secured to the shaft of the roll D¹. The rolls D⁴ and D⁵ are driven in unison by means of gear wheels D⁹ and D⁷.

Below the stripping brushes is placed a basket Q to receive the stockings after they have been removed from the boards by the rotary motion of said brushes.

In Fig. 3 I have illustrated in diagram a view of my device as adapted to a singeing machine and a brief description will serve to show the several elements of such a device.

Referring to Fig. 3 T and T¹ represent the feed rolls of the singeing machine, U is a supporting rod; V and V¹ are gas burners for singeing the stockings as they pass through and C and C¹ are feed rolls which convey the stockings to the air blast and constitute the first set of feed rolls of the device forming the subject matter of my invention. In order to

carry the dust and dirt away from the machine and avoid fouling the air in places where these machines are used I employ a hood W, which is arranged to inclose the space between the feed rolls and from this hood extends a pipe W¹ to convey the dust to a convenient point of exit.

Having described my invention what I claim and desire to secure by Letters Patent is:

1. An attachment for singeing machines comprising feed rolls, air pipes and stripping brushes arranged to coact therewith, the articles to be treated being mounted upon supports, from which they may be stripped by said brushes.
2. An attachment for singeing machines comprising feed rolls, air pipes and stripping brushes arranged to coact therewith, the articles to be treated being mounted upon supports from which they may be stripped by said brushes, and a conveyer leading from said rolls to said brushes.
3. A finishing machine comprising feed rolls, air pipes located so as to coact therewith and provided with jets, a second set of feed rolls, stripping brushes and a conveying means extending from the last named rolls to said brushes the articles to be treated being mounted on supports so as to be acted upon by said brushes.
4. A machine of the type set forth comprising a pair of feed rolls, perforated air pipes arranged in juxtaposition thereto, a second pair of feed rolls rotated oppositely to the first named pair, and located below a horizontal plane projected between the first named feed rolls, stripping brushes arranged in juxtaposition to the second pair of rolls, and an endless belt or conveyer operating between the second pair of feed rolls, the articles to be treated being mounted on supports from which they may be stripped.
5. A machine of the type set forth comprising two feed rolls at one side of the machine,

three feed rolls on the opposite side thereof, air pipes arranged in juxtaposition to the first named rolls and the upper two of the last named rolls, a second set of rolls arranged beneath said first named set and working in conjunction with the lower two of the last named rolls, a conveyer extending between the last named rolls, and stripping brushes arranged in alinement with said conveyer, the articles to be treated being mounted on supports so that they may be stripped from said supports.

6. A finishing machine comprising in combination feed rolls, and stripping brushes arranged to coact therewith, the articles to be treated being mounted on supports so that the articles may be stripped from the supports by said brushes.

7. A finishing machine comprising in combination with the feed rolls, a conveyer, and stripping brushes the articles to be treated being mounted on supports so that the articles may be acted upon by said stripping brushes.

8. A finishing machine comprising in combination with a conveying means, stripping brushes and air pipes arranged above said brushes, said brushes and pipes coacting with said conveying means the articles to be treated being mounted on supports so as to be stripped by said brushes from the supports.

9. The combination with the air supplying means, of stripping brushes, means for conveying the stockings so as to be successively operated upon by the air and brushes, the stockings being mounted on supports so as to be acted upon by said brushes.

In testimony whereof I affix my signature in the presence of two witnesses.

PAUL F. VOGEL.
